Des. 212,866
Patented Dec. 3, 1968

212,866

FOUNTAIN PEN

Roger Perraud, Paris, France, assignor to Société le
Foyer et Cie, Paris, France
Continuation-in-part of design application Ser. No. 7,949,
July 24, 1967. This application Oct. 2, 1967, Ser. No.
8,809

Claims priority, application France Jan. 23, 1967

Term of patent 14 years

(Cl. D74—17)

FIG. 1

FIG. 2

FIG. 3

FIG. 4

FIG. 5

FIG. 6

FIG. 7

FIG. 8

FIG. 9

FIGURE 1 is a top plan view of a fountain pen showing my new design;

FIGURE 2 is a front elevational view,

FIGURE 3 is a side elevational view from the right of FIGURE 2,

FIGURE 4 is a rear view,

FIGURE 5 is a bottom view,

FIGURE 6 is another front elevational view of the fountain pen as it appears in use;

FIGURE 7 is a side elevational view from the right of FIGURE 6,

FIGURE 8 is a rear view, and

FIGURE 9 is a bottom view.

This is a continuation-in-part of my application Ser. No. D. 7,949 filed July 24, 1967.

I claim:

The ornamental design for a fountain pen, as shown and described.
